UNITED STATES PATENT OFFICE

154,970

DESIGN FOR AN EMBROIDERED APPLIQUE

Alise H. Wiggin, Minneapolis, Minn.

Application March 8, 1948, Serial No. 144,958

Term of patent 3½ years

(Cl. D3—9)

To all whom it may concern:

Be it known that I, Alise H. Wiggin, a citizen of the United States and residing in the city of Minneapolis, Hennepin County, Minnesota, have invented a new, original, and ornamental Design for an Embroidered Applique, of which the following is a specification, reference being made to the accompanying drawing, forming a part thereof, wherein:

I claim:

The ornamental design for an embroidered applique as shown.

ALISE H. WIGGIN.
